UNITED STATES PATENT OFFICE.

JOHN CHURCHMAN ROBERTSON, OF GLASGOW, SCOTLAND, ASSIGNOR TO ST. MUNGO MANUFACTURING COMPANY, LIMITED, OF GLASGOW, SCOTLAND.

DESIGN FOR A GOLF-BALL.

52,706.

Specification for Design. Patented Nov. 19, 1918.

Application filed November 20, 1917. Serial No. 203,049. Term of patent 7 years.

To all whom it may concern:

Be it known that I, JOHN CHURCHMAN ROBERTSON, a subject of the King of Great Britain and Ireland, of 185-191 Broomloan road, Glasgow, Scotland, have invented a new, original, and ornamental Design for Golf-Balls, of which the following is a specification, reference being had to the accompanying drawing, forming part thereof.

The figure is a plan view of a golf ball, showing my new design.

I claim:

The ornamental design for a golf ball, as shown.

JOHN CHURCHMAN ROBERTSON.

Witnesses:

RONALD ALBYN McCALLUM,
JANET GRAY.
